(57) **CLAIM**

The ornamental design for a robotic arm, as shown and described.

DESCRIPTION

FIG. 1 is a front view of a robotic arm showing our new design;

FIG. 2 is a top view thereof;

FIG. 3 is a back view thereof;

FIG. 4 is a bottom view thereof;

FIG. 5 is a stretched right view thereof;

FIG. 6 is a stretched perspective right view thereof;

FIG. 7 is a stretched front view thereof;

FIG. 8 is a stretched bottom view thereof;

FIG. 9 is a stretched back view thereof;

FIG. 10 is another stretched right view thereof;

FIG. 11 is a stretched left view thereof;

FIG. 12 is a stretched right perspective view thereof;

FIG. 13 is a stretched top view thereof;

FIG. 14 is a left view thereof;

FIG. 15 is a right view thereof;

FIG. 16 is a perspective view thereof;

FIG. 17 is a right twisted view thereof;

FIG. 18 is a flexed back view thereof;

FIG. 19 is a flexed bottom view thereof;

FIG. 20 is a flexed front view thereof;

FIG. 21 is a flexed left view thereof;

FIG. 22 is a flexed right view thereof;

FIG. 23 is a flexed perspective view thereof; and,

FIG. 24 is a flexed top view thereof.

1 Claim, 17 Drawing Sheets
